CLAIM

The ornamental design for a cable winder, as shown and described.

DESCRIPTION

FIG. 1 is a right, front, top perspective view of cable winder showing my new design.

FIG. 2 is a left, back, top perspective view of the cable winder.

FIG. 3 is a rear elevation of the cable winder.

FIG. 4 is front elevation of the cable winder.

FIG. 5 is a top plan view of the cable winder.

FIG. 6 is a plan bottom view of the cable winder.

FIG. 7 is a left side view of the cable winder, the right side being substantially a mirror image thereof.

FIG. 8 is a bottom, front, right side perspective view of the cable winder; and,

FIG. 9 is a bottom, back, left side perspective view from of the cable winder.
